[57] **CLAIM**

The ornamental design for a combined spirit level and angle-indicating device, as shown and described.

DESCRIPTION

FIG. 1 is a front elevational view of a combined spirit level and angle-indicating device showing our new design;

FIG. 2 is a top plan view;

FIG. 3 is a bottom plan view;

FIG. 4 is a rear elevational view;

FIG. 5 is a left side elevation view; and

FIG. 6 is a right side elevational view.

FIG. 1.

FIG. 2.

FIG. 3.

FIG. 4.

FIG. 5.

FIG. 6.
